UNITED STATES PATENT OFFICE.

EDWARD J. MANNING, OF NEW YORK, N. Y., ASSIGNOR TO THE WAGNER TYPEWRITER COMPANY, OF SAME PLACE.

TABULATING MECHANISM FOR TYPE-WRITERS.

SPECIFICATION forming part of Letters Patent No. 609,517, dated August 23, 1898.

Application filed June 15, 1897. Serial No. 640,843. (No model.)

To all whom it may concern:

Be it known that I, EDWARD J. MANNING, a resident of the city, county, and State of New York, have invented certain new and 5 useful Improvements in Tabulating Mechanism for Type-Writers, of which the following is a specification.

My invention relates to what is known as "tabulating mechanism" for type-writers— 10 that is to say, mechanism particularly available for writing bills, invoices, statements of account, &c., wherein tabulation of the work written is necessary and wherein the touching of a certain key or lever allows the carriage 15 to travel across the machine from right to left and causes the carriage to be automatically stopped at a certain predetermined point, when the writing may be continued, as before. In machines of this character heretofore devised 20 a depression of the tabulating-key would result in the carriage being rapidly propelled by its spring across the machine, and the sudden stopping of the carriage by the adjustable stop would result in jarring the entire 25 machine and render the parts liable to become broken.

The object of my invention is to overcome the difficulties heretofore found in machines of the character specified and to provide a 30 type-writer with tabulating mechanism wherein the speed at which the carriage travels across the machine is under the control of the operator, so that the jar upon the parts may be overcome and the liability of 35 damage decreased.

In the accompanying drawings, wherein like reference characters indicate corresponding parts in all the views, Figure 1 is a vertical transverse section of Fig. 2, showing 40 sufficient number of parts of a type-writer to illustrate my invention. Fig. 2 is a rear view of the same. Fig. 3 is a top view of a portion of the same with parts broken away. Figs. 4 and 5 are enlarged detail perspective and 45 bottom views, respectively, of the tabulating-stop and its carrying-frame.

In the drawings, A represents the framing of a type-writer, in which various parts of the device are mounted. Upon the framing A is 50 carried a suitable carriage B, which is adapted to traverse the framing and is provided with

suitable feeding mechanism for feeding the carriage one space at a time in the usual manner. In the present instance this feeding mechanism is shown to comprise a universal bar *a*, against which the heel *b* of a type-bar *C* is adapted to abut before the impact of a type against the paper on the paper- 55 platen *D*. This universal bar *a* is connected, as by means of the links or connecting-pieces *c*, with suitable spring-pressed links *d*, which normally maintain the universal bar *a* in the path of a type-bar *C* in its oscillation to the printing-point. Upon the links *c* or suitable portions carried thereby are the feed- 60 dogs *e f*, which engage alternately a rack *g*, carried by and traveling with the carriage *B*. The feed-dog *e* is made longitudinally movable by means of the slot *h* and is normally maintained in the position illustrated 65 in Fig. 2 by means of a coiled spring *i*. Both of these feed-dogs are adapted to be vibrated in and out of contact with the rack *g* around their pivot *j*, and in order that this may be accomplished a pin *k* is provided, which is 70 carried by a piece *l*, which connects with the feed-dog *f*, but in a movement downward causes a corresponding movement of both feed-dogs to cause them to be disengaged from the rack *g*. A rock-shaft *E* is pivoted at the 75 rear of the machine, which rock-shaft is normally maintained in the position illustrated in Fig. 1 by a coiled spring *z*, which surrounds the shaft. The right-hand end of this rock-shaft is provided with ratchet-teeth *m*, which are engaged by teeth *f** on an adjustable tabulating-stop *F*, which is normally maintained in engagement with the teeth *m* by a spring *n*, the tabulating-stop *F* being pivoted in a frame *G*, which is carried by the rock-shaft 80 *E* and adapted to slide thereon. Projecting upwardly from the rock-shaft *E* is a brake *H*, which is adapted to contact with the framing of the carriage *B* when the rock-shaft has been vibrated in the direction of the arrow, Fig. 1. 85 At the point where the brake *H* bears against the carriage *B* said carriage is provided with a strip *I* of leather or other suitable material to prevent a scratching noise and to facilitate the action of the brake. It is of course 90 obvious that this strip of leather may be carried upon the brake, but I prefer to place it 95

upon the carriage in the manner shown. The upper portion of the brake H is provided with a scale which corresponds to a portion of the ordinary scale upon the type-writer, which is used to determine the position of the paper-platen with relation to the printing-point. Coöoperating with the scale on the brake H is a pointer o, carried by the adjustable tabulating-stop F. A handle p is likewise connected to the adjustable tabulating-stop for the purpose of disengaging teeth f* on said stop from the rack m and setting the stop at any point it is desired to stop the carriage for tabulating work, the scale on the brake H facilitating the determination of location of the tabulating-stop. A spring o* tends to normally maintain the teeth on the stop in engagement with the rack m. From the under side of the rock-shaft E projects a finger q, which bears against the pin k, carried by the feed-dogs of the feeding mechanism, so that when the rock-shaft is vibrated in the direction of the arrow in Fig. 1 the feed-dogs will be thrown out of engagement with the rack g and the carriage will be free to move from right to left across the machine. A pivoted link r is connected to a depending arm s of the rock-shaft E and is adapted to be vibrated by an arm t, connected with a tabulating-key J, which projects to the front of the machine and is under the control of the operator. This tabulating-key J is so arranged that the harder it is depressed the greater will be the pressure exerted upon the carriage by the brake H. By this arrangement it will be seen that the ordinary carriage-feeding mechanism may be operated without in any way affecting the operation of the tabulating mechanism, since the pin k can be vibrated backward and forward with the feed-dogs without moving the finger q, which coöperates therewith to throw the dogs out of engagement. However, when it is desired to operate the tabulating mechanism it is merely necessary to depress the tabulating-key J, when the rock-shaft E will be vibrated in the direction of the arrow, Fig. 1, thereby causing the finger q, connected therewith, to force the feed-dogs e f out of engagement with the feed-rack g, and will simultaneously apply the brake H to the carriage, and will at the same time vibrate the adjustable tabulating-stop F into the path of the abutment u upon the carriage, and thereby automatically stop the carriage at any predetermined point. When the finger is released from the tabulating-key, the parts resume their normal position, and the operator may continue to write as before. I have stated that a depression of the tabulating-key J will result in automatically applying the brake at the same time that the feeding mechanism is disengaged and the tabulating-stop interposed in the path of the abutment on the carriage. This is true only when the tabulating-key is depressed and maintained down with some

considerable pressure, since a very slight depression of the tabulating-key will release the feeding mechanism and interpose the tabulating-stop into the path of the abutment 70 on the carriage, but will not be sufficient to force the brake H into contact with the carriage, so that if it is desired to allow the carriage to be propelled by the spring with considerable force across the machine it can be 75 accomplished. The greater the pressure exerted upon the tabulating-key the greater will be the force applied to the brake, so that it will be seen that the carriage can be allowed to travel at any rate of speed desired. 80

While I have shown and described one form of mechanism for carrying out my invention, I would have it understood that I do not wish to limit myself to this particular construction, inasmuch as I am aware that various 85 modifications may be made without departing from the spirit of my invention, which consists, broadly, in providing tabulating mechanism wherein the speed of the carriage is maintained under control of the operator 90 when the tabulating mechanism is being put in operation.

What I claim, and desire to secure by Letters Patent, is—

1. In a type-writer, the combination of a 95 movable carriage, tabulating mechanism for causing said carriage to move any desired number of spaces according to adjustment and means for controlling the speed of said carriage in its movement in the direction of 100 its feed, and mechanism for throwing the controlling means into and out of operation at will.

2. In a type-writer, the combination of a 105 movable carriage, tabulating mechanism for causing said carriage to move any desired number of spaces according to adjustment and a brake for controlling the speed of said carriage in its movement in the direction of its feed.

3. In a type-writer, the combination of a 110 movable carriage, tabulating mechanism for causing said carriage to move any desired number of spaces according to adjustment, a brake for controlling the speed of said carriage in its movement in the direction of its feed and means under control of the operator for applying said brake.

4. In a type-writer, the combination of a 115 movable carriage, tabulating mechanism for causing said carriage to move any desired number of spaces according to adjustment, a brake and means under control of the operator for applying said brake and varying the pressure thereon to control the speed of the 120 carriage in its movement in the direction of its feed.

5. In a type-writer, the combination of a 125 movable carriage, tabulating mechanism for causing said carriage to move any desired number of spaces according to adjustment, means for controlling the speed of said car-

riage in its movement to a predetermined stopping-point and connections between said tabulating mechanism and controlling means, whereby an operation of the tabulating mechanism may effect an operation of the controlling means.

6. In a type-writer, the combination of a movable carriage, feeding mechanism therefor, an adjustable tabulating-stop, means for throwing said feeding mechanism out of operation and the adjustable stop into operation and means under control of the operator for controlling the speed of the carriage in its movement to the stopping-point determined by the adjustable tabulating-stop.

7. In a type-writer, the combination of a movable carriage, feeding mechanism therefor, an adjustable tabulating-stop, means for simultaneously throwing said feeding mechanism out of operation and the adjustable stop into operation and a brake under control of the operator for controlling the speed of the carriage in its movement to the stopping-point determined by the adjustable tabulating-stop.

8. In a type-writer, the combination of a movable carriage, feeding mechanism therefor, an adjustable tabulating-stop, means for throwing said feeding mechanism out of operation and the adjustable stop into operation and a brake for controlling the speed of the carriage in its movement to the stopping-point determined by the adjustable tabulating-stop, said brake being connected with and operated by the means for throwing the feeding mechanism out of and the adjustable stop into operation.

9. In a type-writer, the combination of a movable carriage, feeding mechanism therefor, means for operating the said feeding mechanism at each operation of a type-bar or spacing-bar, an adjustable tabulating-stop, means for throwing said feeding mechanism out of operation and the adjustable stop into operation and means under control of the operator for controlling the speed of the carriage in its movement to the stopping-point determined by the adjustable tabulating-stop.

10. In a type-writer, the combination of a movable carriage, feeding mechanism therefor, means for releasing the feeding mechanism so as to allow of a free movement of the carriage in the direction of its feed, a brake and means for applying said brake to the carriage to control the speed of the carriage in its movement in the direction of its feed.

11. In a type-writer, the combination of a movable carriage, feeding mechanism therefor, means for releasing the feeding mechanism so as to allow of a free movement of the carriage in the direction of its feed, a brake and means under control of the operator for applying said brake to the carriage with variable degrees of pressure to control

the speed of the carriage in its movement in 65 the direction of its feed.

12. In a type-writer, the combination of a movable carriage, feeding mechanism therefor, an adjustable tabulating-stop, a brake for controlling the speed of the carriage in 70 its movement to the stopping-point determined by the adjustable tabulating-stop and a key for simultaneously throwing the feeding mechanism out of operation and the adjustable stop and brake into operation.

13. In a type-writer, the combination of a movable carriage, feeding mechanism therefor, an adjustable tabulating-stop, a brake for controlling the speed of the carriage in 75 its movement to the stopping-point determined by the adjustable tabulating-stop and a key for simultaneously throwing the feeding mechanism out of operation and the adjustable stop and brake into operation, the brake being so connected with the key that 80 the harder the key is depressed the greater 85 will be the pressure exerted upon the brake.

14. In a type-writer, the combination of a movable carriage, a rock-shaft, a brake carried thereby and adapted to bear against the 90 carriage and retard its movement in the direction of its feed and a key connected with said rock-shaft.

15. In a type-writer, the combination of a movable carriage, feeding mechanism therefor, a rock-shaft, a brake carried thereby and adapted to bear against the carriage and retard its movement, an adjustable stop carried by said rock-shaft, a projection extending from the rock-shaft and adapted to engage a portion of the feeding mechanism and throw the same out of operation and a key connected with said rock-shaft whereby a depression of the key will cause the feeding mechanism to be disengaged, the brake to be 95 applied and the stop to be interposed in the 100 path of an abutment on the carriage.

16. In a type-writer, the combination of a movable carriage, feeding mechanism therefor, a rock-shaft, a brake carried thereby and adapted to bear against the carriage and retard its movement, an adjustable stop carried by said rock-shaft and having a pointer 110 which is adapted to coöperate with the scale 115 on the brake to indicate the position of the stop, a projection extending from the rock-shaft and adapted to engage the dogs of the feeding mechanism and throw the same out of operation and a key connected with said rock-shaft whereby a depression of the key 120 will cause the feeding mechanism to be disengaged, the brake to be applied and a stop to be interposed in the path of an abutment on the carriage.
